UNITED STATES PATENT OFFICE.

DELAMAR C. KINNEAR, OF WATERBURY, CONNECTICUT, ASSIGNOR TO THE AMERICAN BRASS COMPANY, OF WATERBURY, CONNECTICUT, A CORPORATION OF CONNECTICUT.

METAL-DRAWING APPARATUS.

Application filed March 23, 1927. Serial No. 177,529.

My invention relates to a metal-drawing apparatus and has for its object to provide an apparatus for coupling two cable ends together by drawing a tubular metallic member surrounding the two ends so as to cause it to engage said ends and form a strong holding contact therewith. It further has for its object to provide a new and improved die and die holder for such apparatus. It further has for its object to provide an apparatus which can be easily assembled and taken apart when desired.

The following is a description of an embodiment of my invention, reference being had to the accompanying drawings, in which:

Figure 1 is a side elevation of a hand tool embodying my invention;

Fig. 2 is an end elevation of the same;
20 Fig. 3 is a section on the line 3—3, Fig. 1;
Fig. 4 is a section on the line 4—4, Fig. 3;
Fig. 5 is a section on the line 5—5, Fig. 1;
Fig. 6 is a section on the line 6—6, Fig. 1;
Fig. 7 is a similar section with one-half of

25 the die removed;

Fig. 8 is a perspective view of one-half of the drawing die;

Fig. 9 is a section on the line 9—9, Fig. 1; and

30 Fig. 10 is a perspective view of a removable holding clamp face-member.

Referring more particularly to the drawings, 2 is a support for a slide 4 carried thereby and having a socket 6 for a two-part drawing die 8. This two-part drawing die has a circumferential groove 10, into which extend projections 12 carried by the die socket so that when the two portions of the die are turned into the positions shown in Fig. 6 portions of the groove in each die member are engaged thereby, and when the die is turned in the position shown in Fig. 7, one die member is disengaged so that it can be withdrawn therefrom so as to unblock the slot 14. The socket has in one side the slot 14 making the socket opensided so that a strand of cable with a sleeve conductor thereon can be passed therethrough and thus laterally introduced into or withdrawn from the die. After lateral introduction the removed portion of the die is replaced and the die turned to the position shown in Fig. 6, in which position the two portions of the die are engaged by the projections 12 so as

to be held within the socket, and after the drawing operation is completed the die section is removed so that the cable can be withdrawn laterally through the slot 14.

The slide 4 is provided on its bottom face with ratchet teeth 16, with which engages a ratchet 18 pivotally mounted by a trunnion at 20 in a socket on one arm of a lever 22 which lever is also provided with a trunnion 24 which enters a bearing socket in the support 2, the pawl trunnion and its socket being located between the trunnion 24 and the slide 4. 26 is a spring wound about a pin 28. One end of the spring bears against the pawl 18 so as to hold it in engagement with the ratchet teeth on the bottom of the slide, 70 while the other end engages the lever 22. The pin 28 is removable and acts as a stop for the shoulder 30 formed upon the lever 22 to limit its movement. The lever 22 is provided with a hand-grip 32 and from the support 2 extends another lever 34 rigidly connected thereto and provided with a hand-grip 36.

Rigidly connected to the support 2 is a clamp jaw 38 with which cooperates a clamp-
ing arm 40 pivoted at 42 and held in position by a clamp bolt 44 swinging about the pivot 46, the jaw and arm being provided with removable faces 39 and 41.

The drawing dies and the clamp faces are 85 respectively provided on their outer ends with shoulders 9 and 47 abutting the corresponding ends of their sockets so that no other means are necessary for preventing their longitudinal movement within their 90 sockets during the drawing operation.

The pawl 18 is provided with a pin 48 forming a handle by which the pawl 18 can be manually retracted against the action of the spring 26 so as to disengage the pawl 95 from the rack upon the slide, so as to permit the slide to be retracted.

In using this tool a tubular coupling member 50 is passed over the two ends 52—54 of a cable, which may be composed of a single 100 strand. This tubular member has a reduced portion 56 which, after the member is placed upon the two ends of the cable, can be passed laterally through the slot 14 and located between the two parts of the drawing die 8, one part of the drawing die being removed during this insertion and afterward restored in place, the two parts being

then turned to the position shown in Fig. 6 so as to be held within the socket by the engagement of the pins 12 with portions of the groove in the two parts thereof. If 5 desired the tubular member can be threaded through the die 8 without removing either part and the cable ends then inserted. After the parts are assembled within the tool the arm 40 of the clamp carried by the support 10 is then secured in place about the reduced portion 56 so as to firmly clamp the same. The lever 22 is then reciprocated, actuating the pawl 18, and causing it to engage the rack 16 upon the slide 4 and move the slide 15 from right to left (Fig. 2) so as to cause the drawing die to move away from the clamp. This draws the metal of the tubular member 50, bringing it into intimate relation with the two ends of the cable within 20 it, causing it to assume a strong holding action with the two ends so that the two ends are coupled together in a positive manner.

When the coupling member and end portions of the cable are placed in the apparatus, the slide 4 is preferably moved so that the die is closely adjacent to the clamp. The parts in Figs. 1 and 5 are, for the purpose of clearness, shown with the die somewhat removed from the clamp as they would be after the coupling member and cable ends have been placed in the tool and the lever 22 actuated so as to move the slide somewhat to the left.

When the full length of the tubular coupling member has been drawn, the arm 40 is opened so as to release the coupling member and the drawing die within the socket 6 having by that time passed over the coupling member, the die portions can be turned to the position shown in Fig. 7 so that one of them can be removed as there shown and the cable withdrawn laterally through the slot 14.

To restore the parts to their initial position, the pawl 18 is withdrawn from the rack 16 by the handle 48 and the slide 4 pushed or retracted to initial position.

The support has an overhanging portion 58 beneath which an upper portion 60 of the lever 22 and the tooth portion of the pawl 18 normally extend so that the trunnions of the lever 22 and the pawl 18 are thereby held within their sockets. If, however, the pin 28 is removed, the pawl 18 can be swung downward so that the trunnion of the pawl can be removed from its socket and the lever 22 can thereafter be swung outward until the portion 60 is withdrawn from the overhang, whereupon the trunnion of the lever 22 can be withdrawn from its socket. By reason of this construction the pawl, lever and support can be easily assembled and disassembled. 62 is a friction 65 spring.

For use in couplings of different sizes, drawing dies of different diameters can be substituted. The clamp is made with removable clamping faces so that clamps suitable for couplings of different sizes may be substituted one for the other.

As will be evident to those skilled in the art, my invention permits various modifications without departing from the spirit thereof or the scope of the appended claims. 75

What I claim is:

1. In a device of the character described, the combination of a support, a slide movably mounted on said support and provided with a series of teeth, a clamp and a die, one 80 mounted rigidly on said support and the other on said slide, a pawl engaging said slide, and means carried by said support for reciprocating said pawl so as to successively engage said teeth and move said die and 85 clamp away from each other.

2. In a device of the character described, the combination of a support, a slide movably mounted on said support, a clamp rigidly mounted on said support and provided 90 with a series of teeth, a die rigidly mounted on said slide so as to be carried thereby, a pawl engaging said slide, and means carried by said support for reciprocating said pawl so as to successively engage said teeth 95 and move said die away from said clamp.

3. In a device of the character described, the combination of a support, a slide movably mounted on said support, a clamp and a die, one mounted rigidly on said support 100 and the other on said slide, a pawl engaging said slide, and means carried by said support for reciprocating said pawl so as to move said die and clamp away from each other, said means comprising a lever pivotally connected to said support, one arm of 105 which engages and actuates said pawl, and a second lever rigidly connected to said support.

4. In a device of the character described, 110 the combination of a support, a slide movably mounted on said support, a clamp and a die, one mounted rigidly on said support and the other on said slide, a pawl engaging said slide, means carried by said support for 115 reciprocating said pawl so as to move said die and clamp away from each other, said means comprising a lever pivoted to said support and to said pawl on different centers, and a second lever rigidly connected 120 to said support.

5. In a device of the character described, the combination of a support, a slide movably mounted on said support, a clamp and a die, one mounted rigidly on said support 125 and the other on said slide, a pawl engaging said slide, means carried by said support for reciprocating said pawl so as to move said die away from said clamp, said means comprising a lever pivoted to said support and 130

to said pawl on different centers, and a second lever rigidly connected to said support, the pivot of said pawl being between said slide and the pivot of said lever to said support.

6. In a device of the character described, the combination of a support, a slide movably mounted on said support, a clamp rigidly mounted on said support, a die rigidly mounted on said slide so as to be carried thereby, a pawl engaging said slide, means carried by said support for reciprocating said pawl so as to move said die away from said clamp, said means comprising a lever pivoted to said support and to said pawl on different centers, and a second lever rigidly connected to said support, said pivots comprising separable sockets and trunnions and said support having an overhanging normally engaging said lever and pawl so as to hold said trunnions within said sockets, and a removable stop preventing the withdrawal of said lever and pawl from beneath said overhang, said lever and pawl being withdrawable from beneath said overhang when said stop is removed.

7. In a device of the character described, the combination of a support, a slide mov-

ably mounted on said support, a clamp and a die, one mounted rigidly on said support and the other on said slide, a pawl engaging said slide, and means carried by said support for reciprocating said pawl so as to move said die away from said clamp, said die being longitudinally split and having a cylindrical exterior and said die carrying member having a circular open-sided socket in which said cylindrical die fits.

8. In a device of the character described, the combination of a support, a slide movably mounted on said support, a clamp and a die, one mounted rigidly on said support and the other on said slide, a pawl engaging said slide, means carried by said support for reciprocating said pawl so as to move said die away from said clamp, said die being longitudinally split and said die carrying member having a circular open-sided socket in which said die fits, said die having a circumferential groove and said socket having projecting means adapted to engage a portion of the groove in each part of the die.

In testimony whereof, I have signed my name to this specification this 22nd day of March, 1927.

DELAMAR C. KINNEAR.

CERTIFICATE OF CORRECTION.

Patent No. 1,679,906.

Granted August 7, 1928, to

DELAMAR C. KINNEAR.

It is hereby certified that error appears in the printed specification of the above numbered patent requiring correction as follows: Page 2, lines 90 and 91, claim 2, after the word "support" strike out the words and comma "and provided with a series of teeth," and insert the same to follow the word "support" in line 89, same page and claim; and that the said Letters Patent should be read with this correction therein that the same may conform to the record of the case in the Patent Office.

Signed and sealed this 2nd day of October, A. D. 1928.

(Seal)

M. J. Moore,
Acting Commissioner of Patents.
